CLAIM

The ornamental design for a pendant, as shown and described.

DESCRIPTION

FIG. 1 is a front perspective view of a pendant;
FIG. 2 is a front elevation view thereof;
FIG. 3 is a rear elevation view thereof;
FIG. 4 is a left side elevation view thereof, the right side elevation view being a mirror image thereof;
FIG. 5 is a top plan view thereof; and,
FIG. 6 is a bottom plan view thereof.

The broken lines shown in the drawings depict rear portions of a pendant, stones within the pendant and a necklace that form no part of the claimed invention.
